UNITED STATES PATENT OFFICE.

KARL ARNSTEIN, OF FRIEDRICHSHAFEN-ON-THE-BODENSEE, GERMANY, ASSIGNOR TO THE FIRM: LUFTSCHIFFBAU ZEPPELIN, GESELLSCHAFT MIT BESCHRANKTER HAF-TUNG, OF FRIEDRICHSHAFEN-ON-THE-BODENSEE, GERMANY.

ANCHORING MEANS FOR AIRSHIPS.

Application filed August 1, 1922. Serial No. 573,983.

To all whom it may concern:

Be it known that I, KARL ARNSTEIN, a citizen of Czechoslovakia, residing at Friedrichshafen-on-the-Bodensee, Germany, have 5 invented certain new and useful Improvements in Anchoring Means for Airships, of which the following is a specification.

This invention broadly refers to anchoring and transporting means for air ships, 10 particularly of the elongated type, and it is intended to devise means of keeping the air ship securely and floatingly mounted at a suitable distance from the ground, and at the same time allowing it to follow the 15 impulse of the air current in the horizontal direction, without endangering its firm hold on the supporting means.

The means heretofore in use for anchoring air ships and the like consisted essentially in the fixing of a stationary point forward of the front end of the car and upon the gangway by securing ropes to an anchoring point in the ground, while the front and rear portions of the car were kept down 25 simultaneously by human power. This method heretofore particularly employed presents the disadvantage among other drawbacks that very considerable stresses are exerted upon the skeleton frame of the 30 ship by gusts of wind in view of the employment of the flexible rope connection as a connecting means which is not safe against compressing and crushing strain, while on the other hand there is the inconvenience 35 that a large number of men are required for holding the hull and steering it in the direction of the wind.

With a view of avoiding the difficulty first referred to it has already been suggested to provide a rigid connection of some point on the front portion of the skeleton frame of the air ship with some anchoring point which was likewise rigidly connected to the ground. This method, however, involved the drawback that it was impossible 45 in the case of upwardly directed gusts of wind to comply with the necessity of allowing the ship to freely adjust itself of its own accord to the direction of the air current, 50 which is equivalent with the prevention of the rear portion of the car from touching the ground, inasmuch as the violent squalls and gusts of wind then occurring have a tendency to depress the rear portion of the

car against the ground with such vehemence 55 that very serious injuries to the frame of the ship were unavoidable when making use of this kind of anchoring.

With a view of avoiding these difficulties and inconveniences it has been suggested to 60 mount the rear portion of the ship upon a carriage of such a weight that there is no danger of its being unintentionally lifted off from the ground.

This invention is based upon the employment 65 of the carriage with the modification that suitable carriages, substantially such as are used ordinarily for the placing into the shed and withdrawing of the ship therefrom are made use of both for anchoring purposes as well as for the self-adjusting support of the rear portion of the ship. Very 70 considerable advantages are realized by this method which is particularly recommendable where the shed is occupied for the time 75 being, and it becomes necessary to first wait for the departure of the ship housed therein, or in case of the impossibility of housing the ship in the shed on account of the wind prevailing at the time. If it be now 80 desired to dock the ship in the shed it will only be necessary to release the anchoring means, and the moving of the ship may then be proceeded with at once by means of the carriages.

It is of particular advantage in this connection to provide means for raising and lowering the point of rigid anchoring of the air ship in the vertical plane, and by this means the anchoring operation itself 85 may be facilitated and the free movement of the ship is not interfered with by the dragging on the ground of any portion of the front part of the ship or of the carriage. By placing the anchoring point in 90 the plane coinciding with the dismounting door the embarking and disembarking, and the taking in of freight, of operating means, fluid, ballast and the like may take place without danger even with unfavorable wind 95 conditions.

My invention will be more fully explained with the aid of the accompanying drawing showing by way of example an embodiment of an air ship anchoring device in 100 accordance with my invention.

Fig. 1 being a side elevation, and
Fig. 2 a detail in transverse section.

In Fig. 1, *a* indicates diagrammatically an air ship with housing and withdrawal trucks *d* and *e* mounted upon the pilot car *b* and upon the motor car *c* respectively. The truck *d* is connected to the ground anchor *f* in such a manner that the rocking self-adjustment of the air ship according to the direction of the wind becomes possible.

The wheels of the truck *e* are transversely disposed with relation to the longitudinal axis of the ship and are adapted to move along a well levelled, asphalt coated or concrete surfaced circular track *g* of a diameter to correspond with the size of the ship with the point of anchorage as the center. The truck *e* itself may be of such weight or may be loaded sufficiently to prevent any lifting of the stern of the air ship from the ground by sudden gusts of wind.

Fig. 2 illustrates on an enlarged scale a vertical sectional view of the ground anchoring member. The holder *h* with substantially spherical head is pivotally mounted in a plunger *i* which is adapted to slide in a cylindrical tube *k*, by which means the said holder may be raised or lowered for a certain distance by hydraulic or pneumatic pressure or by any suitable mechanical or electrical means. Ball bearings *l*, *l*², *l*³ and *l*⁴ are provided for the purpose of facilitating rotation. The ball *n* secured to the housing and withdrawing truck indicated at *m* is introduced into the socket *o* of the spherical head of the holder *h* so as to complete the anchorage, and is secured therein by the locking member *p*. The truck is preferably mounted upon the pilot and passenger car in the plane of the door *q*.

While I have herein described my invention in its broad aspects, I do not intend to be limited to the particular construction herein shown by way of example, but various changes and modifications may occur to persons skilled in the art to adapt the device to varying conditions of application, and without deviating from the spirit of my invention, as herein set forth and claimed.

I claim:

1. Anchoring means for air ships and the like, comprising transporting truck means

secured to the ship substantially adjacent its end, means for detachably and pivotally securing said means to the ground, and a substantially circular track with the pivot- 55 ing point of said means as a center.

2. Anchoring means for air ships and the like comprising transporting truck means secured to the ship substantially adjacent one of its ends, substantially rigid anchoring means for detachably and rotatably securing said means to the ground, a substantially circular track with the anchoring means as a center, and additional moving means on said track and carrying the opposite end portion of said air ship. 60

3. Anchoring means for air ships and the like, comprising an air ship, a disembarking door on said air ship substantially 70 adjacent one of its ends, transporting truck means secured to the ship in the vertical plane of said door and supporting said air ship, means rigidly secured to said transporting truck means for pivoting them to 75 the ground, a circular track upon the ground surrounding said pivoting means as a center, and means to support the air ship on said track.

4. Anchoring means for air ships and the like comprising an airship gondola, a joint member connected with said gondola, a socket fixed to the ground and engageable with said joint member, means for raising and lowering said socket, a substantially 85 circular track with the socket as a center and movable transporting means on said track carrying said airship.

5. Anchoring means for airships and the like comprising an airship gondola, a transporting truck connected with said gondola, a joint member fixed to said truck, a socket fixed to the ground, a joint member connected with the airship and engageable with said socket, means for raising and 90 lowering said socket, a substantially circular track with the socket as a center and movable transporting means on said track carrying said airship. 95

In testimony whereof I affix my signature.

KARL ARNSTEIN.
